DISPENSING DEVICE

Anthony Turak, Cleveland, Ohio

Application February 14, 1947, Serial No. 728,515

10 Claims. (Cl. 222—336)

1

My invention relates to dispensers and valve mechanisms and to the mechanism for operating the same.

My invention is adapted for a number of uses and is particularly adaptable for dispensers of the general type shown in my Patent No. 2,061,052, issued November 17, 1936, and to valve mechanisms having an internal part reciprocal in, and longitudinally of, an outer part.

An object of my invention is to provide an improved dispenser and valve mechanism of an economical and efficient construction.

Another object is the provision of an improved mounting for the operating mechanism of a dispenser or valve.

Another object is the provision of a device constructed so that it may be selectively used as a dispensing device and as a valve mechanism.

Another object of my invention is the provision of a lever system for efficiently reciprocating an internal member relative to an external member of a dispenser or valve.

Another object is the provision of an improved mounting for the levers of a dispenser or valve.

Another object is the provision of a mounting which may be selectively positioned on such a device so as to afford adjustability in the operation of the levers for a reciprocating dispenser or valve mechanism.

Another object is the provision of a mounting for levers which may be easily and readily secured in place.

Another object is the provision for adjusting the stroke of the levers on a device of the class described.

And a still further object is the provision of a new construction of a dispenser and its operating parts, which construction is cheaper to fabricate, is simpler to assemble, is adjustable in nature, and produces results not heretofore obtainable.

Other objects and a fuller understanding of my invention may be had by referring to the following description and claims, taken in conjunction with the accompanying drawing, in which:

Figure 1 is a side view of my improved dispenser mounted in the wall of a container and shows the moving parts in retracted position, that is, with the internal receptacle of the device moved to the left as shown in the drawing;

Figure 2 is a view similar to that of Figure 1 and shows the moving parts in an extended position, that is, with the internal receptacle moved to the right as shown in the drawing;

Figure 3 is a cross-sectional view of my device

2

taken through the line 3—3 of Figure 1 and looking in the direction of the arrows 3—3;

Figure 4 is an endwise view of the device as shown in Figure 1 as looking from the right-hand end of Figure 1 to the left-hand end as shown in the drawing;

Figure 5 is a cross-sectional view of the device taken along the line 5—5 of Figure 1 and looking in the direction of the arrows 5—5 in Figure 1;

10 and

Figure 6 is an enlarged view of parts comprising the improved mounting on my device and shows the parts of the mounting in spaced or "exploded" relationship.

15 In the views of the drawing 10 represents a container wall having a hole 11 in which my dispensing device is mounted. As seen in Figures 1, 2 and 3 the inner or left-hand end of the device extends into the container, that is, extends to the left of the container wall 10. My device has an outer cylinder or sleeve 12 of longitudinal form. The cylinder 12 has threads 22 formed thereon at its left-hand end. An inner nut 20 threaded on the threads 22 of cylinder 12 is positioned on the inside of the container and secures the cylinder 12 against longitudinal movement in one direction. An outer nut 21 threaded on the thread 22 of the cylinder 12 is positioned on the outside of the container and secures the cylinder 12 against longitudinal movement in the other direction. Suitable gaskets or seals are provided between the nuts 20 and 21, respectively, and the wall 10 to prevent leakage through the hole 11 around the cylinder 12 as illustrated in Figure 3.

30 35 An inner cylinder or receptacle 13 somewhat longer than the cylinder 12 slidably fits within the cylinder 12. The inner cylinder 13 is adapted to reciprocate to the right and left in the outer cylinder 12. To provide for adjustment of the internal capacity of the inner cylinder 13 a threaded cap or stopper 14 is threadably secured to the end within the container. By moving the stopper 14 the measuring capacity of the receptacle 13 may be suitably varied.

40 45 Near the inner or left-hand end of the internal receptacle 13 there are provided two inlet openings 15. These inlet openings 15 are provided to permit liquid to freely and quickly flow into the receptacle 13 when the receptacle 13 is moved inwardly or to the left in the position shown in Figures 1 and 3. When in this position liquid within the container having the container wall 10 flows through the inlet openings 15 to fill the receptacle 13. The inlet openings 50 55 15 are so positioned that when the receptacle 13

is moved to its extended position, as shown in Figure 2 of the drawing, the inlet openings 15 are entirely closed off and no more liquid may enter the receptacle 13. When the receptacle 13 is held midway between its retracted position and extended position the inlet openings 15 may be partially uncovered to the desired extent to permit liquid to flow through the openings 15 into the receptacle 13.

At the right-hand or outer end of the receptacle 13 there is provided an outlet opening 16 situated in the bottom wall of the receptacle 13. A small hole or air vent 17 is provided in the upper wall of the receptacle 13 immediately above the outlet opening 16. When the receptacle 13 is in its retracted position shown in Figures 1 and 3, the outlet opening 16 and air vent 17 are closed off by the inner walls of the outer cylinder 12 and no liquid may flow outwardly from the receptacle. Upon movement of the receptacle 13 to its extended position shown in Figure 2 the outlet opening 16 is uncovered and liquid within the receptacle may freely fall and flow from the receptacle. In this extended position the air vent 17 is also uncovered to permit air to enter the receptacle as liquid flows from it. Upon movement of the receptacle 13 to a position intermediate of the two illustrated retracted and extended positions, the outlet opening 16 may be partially closed off and the flow of liquid therefrom may be restricted and the amount flowing therefrom in a given period of time is determined by its viscosity in relationship to the affective or uncovered portion of the outlet opening 16.

The receptacle 13 is formed of a cylinder having the stopper 14 positioned at its inner end. At the outer or right-hand end of the receptacle 13 the end wall is formed by an inner end cup 31 pressed into place as shown in Figure 3. An outer end cup 32 is positioned adjacent the cup 31 and extends out over the edge of the cylinder 13. A suitable sealing material 34 is positioned around the circular edge of the cylinder 13 between the cups 31 and 32. The inner cup 31, the outer cup 32 and the sealing material 34 form the outer end wall of the receptacle 13.

The outer end cup 32 extends radially outward from the cylinder forming the receptacle 13 and is then formed to extend back parallel to the axis of the receptacle 13 to form the flange 33. The annular flange 33 accommodates a circular gasket 35 of rubber or other suitable substance adapted to form a seal.

The outer or right-hand end of the outer cylinder 12 has a flange formed thereon. This flange is denoted by the reference character 36. The gasket 35 tightly engages the circular flange 36 and the end face of flange 36 forms a valve seat engaged by the gasket 35.

An end bar or traverse piece 28 is secured to the end of the reciprocal receptacle 13 by means of the bolt 38. The bolt 38 has a square or other non-circular end portion 39 which complementarily fits into a square or similar non-circular recess in the cup end 31. The bolt 38 extends out through an opening in the end wall 32. A square or other non-circular opening is provided in the cross piece 28 and there is a square or non-circular portion 40 of the bolt 38 which fits into such openings. A knurled nut 37 threadably engages the bolt 38 and secures the cross piece 28 to the end of the receptacle 13. By reason of the non-circular form of the portions 39 and 40, the bolt 38 is prevented from

rotating and the cross piece 28 is prevented from turning on the bolt 38. The cross piece 28 has ear portions 29 formed at its ends and disposed at substantially right angles to the main body 5 of the cross piece 28. By the arrangement shown, the cross piece 28 and the ears 29 are made a part of the movable receptacle 13 and so move longitudinally of the cylinder 12 as the receptacle 13 is reciprocated.

To provide for the reciprocal movement of the inner cylinder or receptacle 13 a set of levers is provided. This set of levers is comprised of a pair of first levers 23 arranged parallel to each other on opposite sides of the cylinder 12 and another pair of second levers 24 also arranged parallel to each other on opposite sides of the cylinder 12. The left-hand end of the second levers 24 are pivotally secured to the first levers 23 at a point intermediate the ends of the levers 23 by means of the pivot pins 26. The handle 25 extends across between the outer or right-hand ends of the levers 23.

The right-hand or lower ends of levers 24 are pivotally secured to the ears 29 of the cross piece 25 23 by means of the pivot pins 30. Movement of the levers 24 by movement of the levers 23 causes the cross piece 28 to reciprocate the receptacle 13 in the cylinder 12.

At the lower or left-hand end of the levers 30 23 hub or cup portions 27 are formed integral with the levers 23. The center of the hub or cup portions 27 is the pivot upon which the levers 23 swing as the handle 25 is raised or lowered. Circular openings are centrally located in hubs 27.

An adjustable and selectively positioned mounting is provided in my device for the hub or cup portions 27 whereby the pivot points upon which the levers 23 swing may be changed in 40 location along the length of the cylinder 12.

The mounting for the levers of my device, particularly the pair of levers 23, comprise the pair of yoke members denoted generally by the reference character 42, the coil springs 46, the tension 45 members 49 and the threaded bolts 53. These members are shown in spaced relationship in Figure 6. The yoke members 42 each have an arcuate portion 43 and end portions 44 at its opposite ends. The arcuate portion 43 is adapted to complement the outside cylindrical surface of, and to engage, the cylinder 12. The end portions 44 extend radially outward from the cylinder 12 and on opposite sides of the cylinder 12. The end portions 44 on each side of the cylinder 12 are spaced from, and disposed parallel to, the end portion 44 of the other yoke member 42. The spaced and parallel relationship is well shown in Figure 6. The end portions 44 have an arcuate cross section so that each pair of end portions 44 on the opposite sides of the cylinder 12 together form the major portion of a hollow cylinder but with a slit or gap between the two adjacent end portions 44. The inner surface of each pair of end portions are provided with threads 45. The threads 45 of each pair of end portions 44 are adapted to threadably engage the threaded portion of the bolts 53. In other words, the mated pairs of end portions 44 provide threaded receptacles for receiving the male threads of the two bolts 53.

The pair of tension members 49 of hollow cylindrical form surround and embrace each pair of end portions 44. The inner opening of the tension members 49 accommodates the two end portions 44 inserted therein. To permit the

tension members 49 to accommodate themselves to the outer cylindrical surface of the cylinder 12 and to provide a good engagement between the tension members 49 and the cylinder 12, there are two arcuate recesses 50 formed on the inner end of each tension member 49. The recesses 50 are shaped to complement the outer surface of the cylinder 12 and such that the tension members 49 may tightly engage the cylinder 12. To permit the tension members 49 to fit around the arcuate portions 43 of the yoke members, recesses 51 are provided in the ends of the tension members 49. The recesses 51 on opposite sides of the tension members 49 accommodate the arcuate portions 43 extending from, and connecting, the end portions 44. These recesses 51 are provided on the ends of the tension members 49 next adjacent to the cylinder 12.

There are also provided on opposite sides of the tension members 49 at the end adjacent the cylinder 12, the grooves or recesses 52. The grooves 52 are in line with the slit or gap between the end members 44 disposed on the opposite sides of the cylinder 12.

The coil springs or helixes 46 are positioned around the respective tension members 49. Each coil spring 46 is of slightly larger diameter at its end removed from the cylinder 12 and has its smaller diameter next adjacent the cylinder 12. Each coil spring 46 has an end piece 48 disposed across or radially of the spring 46 at its smaller end adjacent the cylinder 12. The end piece 48 of each spring 46 fits into a groove 52 of a tension member 49 and into the slit or gap between the end portions 44 on the opposite sides of the cylinder 12. The end portions 48 provide an anchor or securement for the small end of each coil spring 46 and by fitting into the groove 52 of each tension member 49 prevent the movement of the coil spring at the end next adjacent to the cylinder 12. The anchoring end 48 extends into a groove 52 on one side of the tension member 49 and extends further into the gap or slit between the end portions 44, and may further extend across into the opposite groove 52 of the tension member. While the anchoring may be obtained by having the end portion 48 caught only in one groove 52 it is found that in assembling and in holding the parts in their proper position it is also desired to have the end portion 48 extend across to the gap or slit between the end portions 44.

At the other and larger end of the coil spring 46 there is provided a hooked end portion 47. The hooked portion 47 is for the purpose of anchoring this other or larger end to the levers 23. The hub or cup portion 27 of the levers 23 have provided therein three equi-distantly positioned small openings 41. The hooked portion 47 of each spring 46 fits within a selected one of the three openings 41. The tension on the spring 46 is adjusted by determining which of the openings 41 the hooked portion 47 is to be engaged in upon assembling of the parts. Figures 1, 2 and 3 show the hooked portion 47 extending out through one of the openings 41 of the hub or cup portion 27. As the hub or cup portion 27 revolves with the swinging of the levers 23 the position of the hooked portion changes. This change of position being illustrated in the comparison of Figures 1 and 2.

A guard or shield member 18 having opposite slots 19 is positioned around the cylinder 12 next adjacent to the container wall 10. The opposite slots 19 permit the guard 18 to be moved

longitudinally of the cylinder 12 toward the container wall 10, the open space provided by the slots 19 accommodating the mountings on opposite sides of the cylinder 12 for the levers 23. The guard 18 is to add to the appearance of the assembled device, to cover the outer nut 21 and is to cover the inner ends of springs 46 and tension members 49 adjacent to the cylinder 12. The hub or cup portions 27 of levers 23 cover and protect the outer ends of spring 46 and tension members 49. The arrangement of the guard members 18 and the cup portions 27 is such that only the heads of the bolts 53 are exposed.

It is to be noted that the non-circular portions 29 and 40 of bolt 38 and their non-rotative engagement in cup 31 and the traverse piece 28 prevent the receptacle 13 from rotating relative to the levers 23 and 24. Thus the outlet opening 16 is always maintained in a down position to permit liquid to flow therethrough when the dispenser is in its extended position.

To mount the dispenser in the hole 11 of the container wall 10 the cylinder 12 with the receptacle 13 therein and having the outside nut 20 mounted thereon but with the inside nut 20 removed therefrom is inserted into the hole 11 from outside the container. The inside nut 20 is then screwed on to the cylinder 12 to the position shown in the drawing. The inside nut 21 is then tightened up against the container wall to compress the gasket or packing adjacent the container wall and to tightly hold the cylinder 12 into the position shown in the drawing.

The mounting for the hub 27 of levers 23 is then positioned on the cylinder 12 by placing the yoke members 42 around the cylinder 12 to embrace the same. The end members 44 of the yoke members are positioned to extend radially out in a horizontal plane on opposite sides of the cylinder 12. The coil springs 46 and tension members 49 are then moved radially inward to surround the respective pairs of end portions 44 on the opposite sides of the cylinder 12. In nesting the respective pairs of ends 44, the springs 46 and tension members 49, the end portions 48 of the spring are positioned in a groove 52 and between the gap or slit between the spaced end portions 44. After the springs 46 and tension members 49 are nested with, and positioned around, the pairs of end portions 44 the bolts 53 are moved radially inward of the cylinder 12 so that the threaded portion of the bolts 53 protrude into the central opening of the tension members 49 and engage in the threaded portion 45 of the end portions 44. The bolts 53 are turned inward to threadably engage the thread 45 in the end portions 44. The head of each bolt 53 engages the outer annular edge of a respective tension member 49. As the bolt 53 is turned inwardly by a screwdriver the head of the bolt presses upon the tension member 49 and forces it inwardly against the cylinder 12 to tightly engage the outer wall of the cylinder 12. As the tension member 49 is pressed inwardly towards the cylinder 12 the end portions 44 threadably engaging the threads of the bolt 53 are pulled radially outward from the cylinder 12 to cause the arcuate portions 43 of the yoke members to flex and tightly engage the cylinder 12 at the top and bottom thereof. There is thus a tight engagement of the yoke members 42 with the cylinder 12, on its upper and lower cylindrical surface. The yoke members are preferably made of a resilient metal such as steel which will permit the yoke members to resiliently flex when the

bolts 53 are turned inwardly and which permits the yoke members to resume their normal arcuate shape when the tension is removed upon the turning of the bolts 53 radially outward. The tension members 49 embracing the end portions 44 also tightly engage the outer cylindrical surface of the cylinder 12 upon the turning inward of the bolts 53 and thus further anchor the yoke members and the mountings carried on their opposite ends to the cylinder 12.

Before the bolts 53 are tightened down to cause firm engagement of the yoke members and tension members with the walls of the cylinder 12 the position of the yoke members and mountings carried thereon is selected by moving the yoke members longitudinally of the cylinder 12 to the desired position. As seen in the drawing there is considerable latitude in the choice of positions where the mountings for the levers 23 may be positioned. While the yoke members and the springs, tension members and bolts carried thereon loosely engage the cylinder 12, they may be slid longitudinally of the cylinder 12 to a desired position such as that shown for example in the views of the drawing. When in the desired location the screw bolts 53 are turned inwardly to cause the tension members to press firmly against the outer surface of the cylinder 12 and to cause the yoke members to resiliently flex and tightly grip the cylinder 12. The mounting provided by the yoke members, springs, tension members and bolts is thus tightly secured to the cylinders 12 and resist further longitudinal movement.

After the mountings are secured in the desired position with the end portion, coil springs, tension members, and threaded bolts disposed horizontally, the levers 23 and 24 are mounted in position. The levers 23 and 24 being made of metal are adapted to flex somewhat so that the hub or cup portions 27 may be resiliently spread apart to permit the hubs 27 to slide over the bolts 53 and down into the position shown in the views of the drawing. With the levers 23 in raised position, the hooked portion 47 of the springs is inserted into one of the small holes 41 in the hub 27. The hooked portion 47 holds the hub portion 27 radially inward toward the cylinder 12 to secure it in the position shown in the drawing and also provides that the levers are resiliently biased in their swinging motion upon the pivot provided by the adjustable mounting described. As the levers 23 are moved downwardly by the handle 25 the springs 46 engaging the cup or hub 27 resiliently resist the downward movement and upon release of the handle 25 the springs 46, acting through the hooked portions 47 on the hub 27 resiliently bias the levers 23 to their upward position illustrated in Figure 1.

The lower extremities of the levers 24 riveted by pivot pins 30 to ears 29 of the transverse piece 28 are secured to the outer end of the receptacle 13 by placing the transverse piece 28 in engagement with the bolt 38 to the position shown in the drawing. The knurled nut 37 is then screwed down at the cross piece 28 to which the levers 24 are pivotally attached and the levers are thus secured to the receptacle 13. The levers may be easily detached from the receptacle by the removal of the knurled nut 37 and the pulling of the transverse piece 28 off the bolt 38. With the levers disengaged from the receptacle 13 the receptacle may easily be withdrawn from the cylinder 12 for cleaning or repair.

From the views of the drawing it is seen that

when the handle 25 is in the upper position, shown in Figure 1, the force of the coil spring causes the levers to retract and move the receptacle 13 into its retracted position of Figure 1. Upon manual movement of the handle 25 downwardly to the position of Figure 2 the action of the levers is such that the receptacle 13 is moved to its extended position to uncover the outlet opening 16 as shown in Figure 2. The degree of the extension 10 of the receptacle 13 out from the cylinder 12 is determined by the length of the levers and by the position of the pivot upon which the levers 23 swing. By moving the mountings for the levers 23 longitudinally of the cylinder 12 the stroke of 15 the levers is adjusted. For universal use of the dispenser it is desirable to have the pivot mounting for the levers 23 adjustable so as to be located as desired along the length of the cylinder 12. Sometimes it is desired to use the device to dispense liquid in measured quantities in which case 20 the receptacle is held in its extended position until its contents have drained off. When thus used it is desired that the outlet opening 16 be entirely uncovered to provide for quick withdrawal of the 25 contents of the receptacle. For this purpose the dispenser would be held in the position of Figure 2 until the contents of the receptacle 13 had flowed therefrom and it would be known that the amount which flowed out would be the full contents of the 30 receptacle as determined by the adjustment of the stopper 14. Sometimes it is desired to use the device as a valve to dispense a smaller quantity of liquid, the quantity then being determined by the time that the handle 25 is held down, the 35 effective uncovered portion of outlet opening 16 and the viscosity of the liquid. For so dispensing quick shots of quantities smaller than the total capacity of the receptacle it may be desired to have the outlet opening 16 only partially uncovered 40 in each reciprocating stroke of the receptacle. To provide only a partial uncovering of the outlet opening 16 when the handle 25 is pushed to its downward position, the location of the pivot mounting for levers 23 may be adjustively determined by moving the mounting longitudinally of the cylinder 12 and securing it in the desired position as described. By a quick manual stroke or flip of the handle 25 a small shot of liquid, less 45 than the capacity of the receptacle, may be dispensed, the size of the shot being determined by the viscosity of the liquid and the time during which the handle 25 is held in a downward position, this being quickly ascertainable from experience.

55 The disclosed device is flexible in operation, is quickly adjustable and efficiently meets the needs for universal use of such dispensers.

Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. In a valve mechanism having an internal member reciprocally mounted within a stationary member and having a pair of levers adapted to reciprocate said internal member, each of said pair of levers having a hub portion adapted to be pivotally carried by said stationary member, a mounting for said levers comprising in combination a pair of yoke members embracing said sta-

tionary member, said yoke members having end portions extending radially outward of said stationary member, said end portions having threads formed thereon, a pair of tension members each embracing adjacent end portions of said yoke members, each said tension member and said end portions embraced thereby forming a substantially concentric assembly, a pair of coil springs each mounted around one of said assemblies, each said coil spring having an inner end anchored to a said assembly and having an outer end anchored to a said hub portion of a respective lever, and a pair of threaded members each threadably engaging the threads of the adjacent end portions of said yoke members, said threaded members also engaging the said tension members, respectively, said threaded members and tension members providing tension therebetween to cause said yoke members to flex and tightly embrace said stationary member, the said assemblies providing pivot mountings, respectively, for said hub portions, and said coil springs providing a bias to movement of said levers on said pivot mountings.

2. In a valve mechanism having a longitudinal member and levers having ends carried by said longitudinal member, a mounting for said lever ends adapted to be secured to said longitudinal member at selected positions along its length, comprising in combination a pair of yoke members embracing said longitudinal member therebetween, each of said yoke members having opposite end portions spaced from, and disposed substantially parallel to, an end portion of the other of said yoke members, said end portions being threaded on their inner surfaces, a pair of tension members each surrounding adjacently disposed end portions of said yoke members, a pair of bolts each threadably engaging the inner surfaces of said adjacently disposed end portions and each engaging a said tension member, said assembled adjacently disposed end portions, tension member and bolt forming a set, a pair of coil springs each carried by a set of said adjacently disposed end portions, tension members and bolts, and each engaging one of said lever ends, each of said lever ends being pivotally carried by a set of said adjacently disposed end portions, tension members, and bolts.

3. A mounting for a pair of levers, said mounting being adapted to be secured to a selected position of a plurality of longitudinally spaced positions along a longitudinal member, comprising a pair of clamping members embracing and clamping said longitudinal member therebetween, each of said clamping members having opposite end portions spaced from, and disposed substantially parallel to, the opposite end portions of the other of said clamping members, a pair of hollow members embracing the said end portions of the pair of clamping members, and threaded means engaging said end portions and said hollow members and providing tension therebetween to clamp said clamping members to said longitudinal member.

4. In a valve mechanism having a hollow outer member, an inner member longitudinally slidable in said outer member, and lever means for reciprocating said inner member relative to said outer member, an improved mounting for said lever means comprising in combination, a pair of resiliently flexible yoke members embracing said outer member, each said yoke member having opposite end portions, said end portions having threads formed thereon, a pair of hollow tension members, each said tension member

being positioned around the adjacent end portions of said pair of yoke members, a pair of helical springs of opposite turn, each said spring being mounted around one of said tension members and being anchored to a respective tension member and said lever means to provide a resilient bias to said lever means, and threaded bolts engaging said end portions at the opposite ends, respectively, of the yoke members, and engaging said tension members, respectively, said threaded bolts providing a pivot support for said lever means and providing opposing forces between said tension members and said end portions to flex said yoke members to tightly engage said outer member.

5. In a dispensing device having a sleeve member, a movable receptacle slidably fitting in said sleeve member and operating levers for reciprocating said receptacle in said sleeve member, 20 said operating levers having a hub portion adapted to be carried by said sleeve member, the improvement of a mounting for said levers, said mounting comprising in combination a pair of yoke members, said yoke members being 25 adapted to embrace said sleeve member, said yoke members having end portions extending radially outward in opposite directions, tension means carried by said end portions for drawing said end portions radially outward in said 30 opposite directions to cause said yoke members to flex radially inward, said yoke members upon being inwardly flexed being adapted to tightly engage said sleeve member, and spring means anchored to said tension means and said 35 hub portions to provide resilient bias to said levers, said end portions, tension means and spring means providing a mounting for support of said levers.

6. A pivot mounting for a pair of levers, said 40 mounting adapted to be clamped to a cylinder at a selected position along the cylinder, a pair of clamping members having resiliently flexible arcuate portions placed on opposite sides of said cylinder at said selected position to embrace the 45 cylinder therebetween, said clamping members having end portions at their opposite ends, the end portions on each side of the cylinder being spaced from each other and having threads formed on their facing surfaces, a hollow member 50 positioned around the end portions on each side of the cylinder, each said hollow member having its end adjacent said cylinder formed to complement the cylindrical surface of said cylinder and to accommodate said arcuate portions of 55 the clamping members, a coil spring positioned around each said hollow member and having an anchor end positioned between said end portions adjacent said cylinder and having an engaging end engaging one of said levers to provide 60 resilient bias to said lever, and a threaded and headed bolt threadably engaging the said facing surfaces of said end portions and abutting an end of said hollow member and providing tension between said clamping members and hollow 65 members, the said tension forcing said hollow members radially inward against said cylinder and pulling said end portions of the clamping members radially outward to resiliently flex said arcuate portions and clamp them against said 70 cylinder, said mounting providing a pivot support for said levers.

7. In a dispenser having a measuring receptacle reciprocal in a cylindrical sleeve member and levers connecting said receptacle and sleeve member for reciprocating said receptacle, the im-

11

provement of means for connecting the said levers to said sleeve member, said means comprising in combination, clamping members adapted to embrace said sleeve member and to be positioned at a selected position along the sleeve member, tension means carried by the opposite ends of the clamping members and adapted to clamp the clamping members to said sleeve member, pivot means carried by said ends for pivotally carrying said levers, and spring means carried by said ends and adapted to provide resilient bias between said ends and said levers.

8. The improvement of a mounting for levers carried by a longitudinal member of a dispenser, said mounting being selectively engageable to said longitudinal member at one of a plurality of positions, comprising oppositely facing yokes embracing said longitudinal member therebetween, tension means carried by said yokes for pulling the ends thereof laterally outward from said longitudinal member, said yokes being sufficiently resilient to flex under said tension and to tightly engage the longitudinal member, and biasing means carried by said yokes for providing bias to said levers, said tension means and biasing means on opposite sides of said longitudinal member providing a pivot mounting for one of said levers.

9. A mounting for a lever, said mounting being adapted to be secured to a selected position of a plurality of longitudinally spaced positions along a longitudinal member, comprising a clamping member having an open space therein for accommodating said longitudinal member, said

5

10

15

20

25

12

clamping member being adapted to embrace and to be clamped to said longitudinal member, said clamping member on a side of said open space having end portions spaced from, and disposed substantially parallel to, each other, a tension member engaging said end portions and flexing said clamping member to clamp said longitudinal member, and biasing means carried by the clamping member for providing bias to said lever, said engaged tension member and end portions providing a pivot mounting for said lever.

10. The improvement of a mounting for a lever carried by a longitudinal member of a dispenser, said mounting being selectively engageable to said longitudinal member at one of a plurality of positions, comprising a clamping member adapted to clamp said longitudinal member, said clamping member having opposing end portions, tension means engaging said end portions to tense said clamping member for clamping engagement on said longitudinal member and biasing means carried by said clamping member at said tension means for providing bias to said levers, said tension means and biasing means providing a pivot mounting for said lever.
